UNITED STATES PATENT OFFICE.

SISSAK K. OUZOUN-BOGHSSIAN, OF WASHINGTON, DISTRICT OF COLUMBIA.

WORKBENCH FOR WATCHMAKERS AND JEWELERS.

1,328,891.

Specification of Letters Patent. Patented Jan. 27, 1920.

Application filed November 4, 1918. Serial No. 261,021.

To all whom it may concern:

Be it known that I, SISSAK K. OUZOUN-BOGHSSIAN, a subject of the Sultan of Turkey, residing at Washington, in the District 5 of Columbia, have invented certain new and useful Improvements in Workbenches for Watchmakers and Jewelers, of which the following is a specification.

This invention relates to improvements in 10 work-benches which are more particularly adapted for watchmakers' use.

The object of my invention is to provide a collapsible work-bench which is a combination of three separate main parts which 15 can be easily carried anywhere desired.

Another object of my invention is to provide an interchangeable work-bench which is a combination of three separate main parts which can be changed to various styles at 20 any time desired.

In the accompanying drawings, Figure 1 is a perspective view of a watchmaker's work-bench constructed in accordance with the invention, in which the three separate 25 main parts are slightly separated from each other at the arrow points. Fig. 2 is a back view of the top main part of the bench. Fig. 3 is a back view of the pedestal separate main parts B and C in Fig. 1, and of 30 the pedestal separate main part in Fig. 4. Figs 4 and 6 are perspective views of the front parts of two styles of pedestal parts, on a smaller scale. Figs. 5 and 7 are front views of other two styles of pedestal main 35 parts, on a smaller scale. Fig. 8 is a back view of the pedestals in Figs. 5, 6 and 7. Figs. 9 and 10 are two styles of side views of the pedestals in Figs. 5, 6 and 7. Fig. 11 is a style of side view of the pedestal in Fig. 4. 40 Fig. 12 is a plan view of the apron drawer M in Fig. 1.

Throughout the drawings the reference characters H indicate the drawers, I indicate the handles of the drawers and the door, L 45 indicate the panels, K indicate the posts, E indicate the railings, S indicate the pegs affixed on top of the pedestals, and R indicate the opening without panels.

In Fig. 1, a set of small drawers H are 50 fitted to the top part A and the pedestal parts B and C. The swing door G is adapted for the setting up the watchmaker's lathe, the opening J with the front part P

is a chalk container, and the apron-drawer M being constructed in the form of a frame 55 as shown in Fig. 12, the bottom of which being closed with either cotton cloth or oil cloth, slides on the railings N, N. The working surface D is about 40 inches long and about 20 inches wide. The top separate 60 main part A and the pedestal separate main parts B and C removably being fitted together, the height to working surface is about 40 inches. Either one of the pedestals in Figs. 4, 5, 6 and 7 can be used in ex- 65 change of the pedestals A and B at any time desired. And by exchange of the top part A with a top part suitable for jewelry workers it can be used by the jewelers.

Having thus described this invention what 70 I desire to secure by Letters Patent of the United States and claim is:

1. A collapsible and interchangeable work-bench more particularly adapted for watchmakers' and jewelers' use comprising a top- 75 part A removably fitted on tops of two pedestal parts, said top part A comprising working surface D fitted with the railings E, a set of five drawers H fitted with the handles I, the opening J, swing door G with 80 the handle I, and the apron drawer M sliding on the railings N, N, said pedestal parts having fixed pegs S, S, said top part A having slots to fit to said pegs S, S, said pedestals of said bench adapted to be used in combination in various styles of pedestals being exchanged, all substantially as set forth.

2. A collapsible and interchangeable work bench particularly adapted for watchmakers' and jewelers' use comprising a top part 90 A removably fitted on tops of two pedestal parts B, C, said top part A being provided with a working surface D, side and back railings E, a set of five drawers H with the handles I, an opening J, swing door G, and 95 the apron drawer M sliding on the railings N, N, said pedestal parts B and C being provided with two sets of drawers H with the handles I, and the pegs S, S, said top part A having slots to fit to said pegs S, S, 100 either of said pedestals B and C of said bench adapted to be used in combination being exchanged with pedestals in Figs. 4, 5, 6 and 7, all substantially as set forth.

3. A collapsible and interchangeable work 105 bench more particularly adapted for watch-

makers' and jewelers' use comprising the top part A removably fitted on tops of two pedestal parts, said top part A being provided with a surface D, railings E, a set of five drawers H with handles I, opening J, swing door G, apron drawer M sliding on the railings N, N, and a set of slots to fit pegs S,

said pedestal parts having fixed pegs S, said pedestal parts of said bench adapted to be used being exchanged with various styles of 10 pedestals in said combination bench, all substantially as set forth.

In testimony whereof I signed my name.

SISSAK K. OUZOUN-BOGHOSIAN.
